CLAIM

The ornamental design for an electronic device holder, as shown and described.

DESCRIPTION

FIG. 1 is a perspective view of an electronic device holder showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a view illustrating a state in which the claimed design is connected to a portable terminal.

In FIG. 3, the broken lines illustrate portions of the portable electronic device that form no part of the claimed design.

In FIG. 8, the broken lines depicting a portable terminal represent environmental subject matter and form no part of the claimed design.
